US0D1106940S

(12) **United States Design Patent** (10) **Patent No.:** **US D1,106,940 S**
(45) **Date of Patent:** **** Dec. 23, 2025**

(54) **BATTERY**

(71) Applicant: **Inventus Power, Inc.**, Woodridge, IL (US)

(72) Inventors: **Elijah Brett Goldin**, Chicago, IL (US); **Timothy James Vallaro**, Batavia, IL (US); **Bryan Rossman**, Warrenville, IL (US); **Daniel Paul Rose**, Wheaton, IL (US); **Marcelo Nicosia**, Oak Park, IL (US); **Horace C. Rodriguez**, Schaumburg, IL (US)

(73) Assignee: **Inventus Power, Inc.**, Woodridge, IL (US)

(**) Term: **15 Years**

(21) Appl. No.: **29/772,527**

(22) Filed: **Mar. 2, 2021**

Related U.S. Application Data

(63) Continuation of application No. 17/085,873, filed on Oct. 30, 2020, now Pat. No. 11,081,755, which is a continuation-in-part of application No. 17/038,287, filed on Sep. 30, 2020, now Pat. No. 11,064,604.

(57) **CLAIM**

The ornamental design for a battery as shown and described.

DESCRIPTION

The sole FIGURE is a front, right perspective view of a battery.

The broken lines immediately adjacent to the shaded area depict boundaries of the claimed design and form no part thereof. Portions of the battery not shown in the drawing form no part of the claimed design.

1 Claim, 1 Drawing Sheet
